(57) **CLAIM**

The ornamental design for an irrigation controller housing, as shown and described.

DESCRIPTION

FIG. 1 is a front perspective view of my new design for an irrigation controller housing, having the front cover in an open position;

FIG. 2 is a front elevation view of the irrigation controller housing shown in FIG. 1;

FIG. 3 is a rear elevation view of the irrigation controller housing shown in FIG. 1;

FIG. 4 is left side view of the irrigation controller housing shown in FIG. 1;

FIG. 5 is a right side view of the irrigation controller housing shown in FIG. 1;

FIG. 6 is a top plan view of the irrigation controller housing shown in FIG. 1;

FIG. 7 is a bottom plan view of the irrigation controller housing shown in FIG. 1;

FIG. 8 is a front perspective view of my new design for an irrigation controller housing, having the front cover in a closed position;

FIG. 9 is a front elevation view of the irrigation controller housing shown in FIG. 8;

FIG. 10 is a rear elevation view of the irrigation controller housing shown in FIG. 8;

FIG. 11 is left side view of the irrigation controller housing shown in FIG. 8;

FIG. 12 is a right side view of the irrigation controller housing shown in FIG. 8;

FIG. 13 is a top plan view of the irrigation controller housing shown in FIG. 8; and,

FIG. 14 is a bottom plan view of the irrigation controller housing shown in FIG. 8.

Broken lines shown in the drawings form no part of the claimed design. Oblique lines shown in the drawings indicate transparent or translucent surfaces.

1 Claim, 12 Drawing Sheets
